UNITED STATES PATENT OFFICE.

WILLIAM S. SHARPNECK, OF CHICAGO, ILLINOIS, ASSIGNOR TO FRANCIS T. WHEELER, OF SAME PLACE.

SPEED-GOVERNOR FOR GAS-ENGINES.

SPECIFICATION forming part of Letters Patent No. 441,024, dated November 18, 1890.

Application filed February 5, 1890. Serial No. 339,277. (No model.)

To all whom it may concern:

Be it known that I, WILLIAM S. SHARPNECK, a citizen of the United States, residing at Chicago, in the county of Cook and State 5 of Illinois, have invented certain new and useful improvements in Speed-Governors for Gas-Engines, of which the following is a specification, reference being had therein to the accompanying drawings.

10 My invention relates to speed-governors, and has especial reference to a governor for use upon gas-engines, although it may be used upon other engines and be effective for the intended purpose.

15 The object of my invention is the provision of a governor which will be superior to others in simplicity, inexpensiveness, and general efficiency.

To attain the desired object, my invention 20 consists of the novel construction and combination of parts, substantially as illustrated, described, and specifically claimed.

I have illustrated my governor as applied to the gas-engine and valve which I have applications for of even date herewith; but I would have it understood that I do not limit myself to its employment upon the same, but reserve the right to use it upon any engine 25 where it will operate; and in said drawings—

30 Figure 1 represents a plan of the engine with valve and governor applied, the valve and governor being represented in section. Fig. 2 represents a plan view, partly sectional, of the governor, the parts being shown in the 35 position they occupy when the charge is admitted to the engine. Fig. 3 represents a similar view, the parts being in the position they occupy when the gas-port is closed or when the charge is prevented from entering

40 the engine. Fig. 4 is a detail showing part of the governor-cylinder and a spring relief-cock, an edge view of the latter being also shown below it. Fig. 5 is a face view of a cam-disk and its attached parts.

45 Referring by numerals to the drawings, in which similar numerals of reference denote corresponding parts in the several figures, the numeral 1 designates the engine, 2, the valve-case, and 3 the valve, the construction and 50 operation of which are fully illustrated and described in the applications therefor presented by me of even date herewith and serially

numbered 339,278 and 339,279. Communicating with the inlet-port of the valve-case is the charging-pipe 4, through which the charge of 55 air and gas enters, and which is provided with an opening 5, with which communicates the gas-inlet pipe 6. The gas-inlet pipe leads from the cylinder 7, having the inlet 8 for the gas, the sleeve or barrel 9, the air-escape opening 10, (see Fig. 4,) and the series of openings 60 11, the purpose of which will presently appear. Fitting in one end of the cylinder is the piston-valve 12, which comprises two pistons arranged sufficiently far apart to allow a 65 free passage for gas through the inlet 8 into the pipe 6 when the valve is in one position. The upper part of the cylinder thus forms a valve-case.

To the outer face of the outer disk of the 7c valve is connected (in this instance by means of a short bar) the outer end of the spring-actuated rod 13, which is arranged in the barrel or sleeve 9 of the cylinder 7, and the outer end of the rod is rounded at 14 and provided 75 with a lug or shoulder 15. This rod is reduced in size for the major part of its length, which part is made springlike, and is so arranged as to always tend to carry its lower end toward a cam-disk 20, hereinafter referred to. 80

On the shaft of the valve is an eccentric 16, with which engages the yoke 17 of the rod 18, which carries the piston 19, arranged and working in the cylinder 7, and on said shaft adjacent to the eccentric is a wheel or disk 85 20, (shown in a larger scale in Fig. 5, which shows the face of said disk,) which carries a cam 21, a lug 22, and is flanged at 23, said flange being reduced at 24, the purpose of which will appear. 90

Above the opening 10 of the cylinder 7, I pivot a spring relief cock or slide 25, having a handle for the ready manipulation thereof, and an opening 25^x adapted to communicate with the escape-opening 10 to regulate the escape and govern the speed, and on the under side a pin or stud adapted to enter the openings in the scale or indicator 26. 95

This being the construction of my governor, the consequent operation is as follows: The 100 ports being in their normal position, as shown in Figs. 1 and 2, allowing the charge of gas and air to pass into the cylinder, the cam 21 revolves in the direction of the arrow, (see

Fig. 5,) and acting upon the rounded end 14 of the spring-actuated rod 13, causing it to move in the direction of the arrow, (see Figs. 2 and 3,) and the resiliency of the spring portion of said rod 13 causes the lug 15 to slide over and ride upon the flange 23 of the disk 20, thus closing the entrance to the pipe 6, as shown in Fig. 3. The lug 15 remains on the flange 23 until the reduced portion 24 arrives in line with the lug 15, when, if the engine is running at its normal speed, the pressure of the spiral spring around the rod 13 causes it to descend, and thus allows the gas to enter, as before. Should, however, the engine be running too fast, the piston 19 will compress the air into the space between said piston and the piston-valve above it faster than it can escape through the relief-cock, which will prevent the descent of the rod 13 until the lug 22 on the cam-disk 20 passes under the lug 15 and guides the latter onto the flange 23, where it is retained, keeping the piston-valve 12 in the position shown in Fig. 3, and preventing the passage of the gas through the pipe 6 until the speed of the engine has moderated, when the pressure of the compressed air between the piston and piston-valve is no longer sufficient to prevent the rod 13 descending, and by carrying the valve with it allow the gas to pass through the pipe 6, when the previous operations are repeated. Thus it will be seen that the valve is opened and closed by the action of the cam and the spring-actuated rod, and the engine charged at proper intervals; but should the engine begin to run at a greater speed than is required and necessary the action of the piston 19 in the cylinder 7 would compress the air between it and the valve and force said valve outward, closing it and preventing gas from entering. When the engine returns to its proper speed the parts act as before described, and as the engine begins to run at a higher speed than is required it is governed by the action of the piston.

It is evident that the valve is operated by the rod and cam while the engine is running at the proper rate of speed, and that the action of the piston is quickened as the engine runs faster and compresses the air between said piston and the valve and retains said valve in position to close the gas-inlet until the speed is reduced.

It will thus be seen that I provide a very simple governor, which is thoroughly efficient and will govern the speed of the engine in a perfect manner.

I would also have it understood that I do not limit myself to the construction herein described, as I may make changes in the same without departing from the spirit or sacrificing any of the advantages of my invention.

The series of openings 11 on the cylinder 7 are to allow air to be drawn into the cylinder.

I claim as my invention—

1. In a speed-governor, a valve-case, inlet and outlet ports therein, two connected pistons, one of which acts as a valve and closes the outlet-port, and the two arranged in opposite sides of the inlet-port, and means, as the piston 19, for acting on the air inclosed between the piston and the valve to operate said valve, substantially as described. 65

2. In a speed-governor, a valve-case, inlet and outlet ports therein, two connected reciprocating pistons, one of which acts as a valve and closes the outlet-port and the two arranged in opposite sides of the inlet-port, and a reciprocating piston acting on the air inclosed between the piston and valve, substantially as described. 75

3. In a speed-governor, a cylinder, inlet and outlet ports therein, two connected reciprocating pistons, one of which acts as a valve and closes the outlet, and the two arranged in opposite sides of the inlet-port, a reciprocating piston in the other end of the cylinder acting upon the air inclosed between the piston and piston-valve, substantially as described. 85

4. In a speed-governor, a cylinder 7, the inlet 8, the pipe 6, leading from the cylinder, double piston-valve 12, the reciprocating piston 19, and the spring-actuated rod 13 to return the valve against the pressure in the cylinder, substantially as described. 90

5. In a speed-governor, a cylinder 7, having inlet 8 and outlet 6, a reciprocating piston 19, a double piston-valve 12, a spring-actuated rod connected with said valve and having rounded end 14 and lug 15, in combination with the revolving disk 20, having cam 21, lug 22, flange 23, and reduced portion 24, substantially as described. 100

6. In a speed-governor, a cylinder 7, the inlet 8, the pipe 6, leading from the cylinder, the double piston-valve 12, the reciprocating piston 19, the spring-actuated rod 13 to return the valve against the pressure in the cylinder, an opening in the cylinder to admit of the passage of the air from the same, and the adjustable spring relief-cock 25, governing the passage of the air through said opening, substantially as described. 105

7. In a speed-governor, the combination of the valve, the rod connected thereto and having the lug, the cam engaging said rod, the disk having the flange to receive the lug on said rod, and the lug for engaging said lug, substantially in the manner and for the purpose specified. 115

In testimony whereof I affix my signature, in presence of two witnesses, this 31st day of January, 1890.

WILLIAM S. SHARPNECK.
